DESIGN FOR A COMBINED BICYCLE GUARD AND LAMP

George S. Lewis, Oak Park, Ill., assignor to Battery Patents Corporation, Chicago, Ill., a corporation of Illinois

Application December 28, 1934, Serial No. 54,623

Term of patent 14 years

To all whom it may concern:

Be it known that I, George S. Lewis, a citizen of the United States of America, residing in Oak Park, in the county of Cook and State of Illinois, have invented a new, original, and ornamental Design for a Combined Bicycle Guard and Lamp, of which the following is a specification, reference being had to the accompanying drawing, forming a part thereof, in which—

Fig. 1 is a side elevational view of a combined bicycle guard and lamp, showing my new design; and

Fig. 2 is a cross-sectional view taken on the line 2—2 of Fig. 1.

I claim:

The ornamental design for a combined bicycle guard and lamp, substantially as shown.

GEORGE S. LEWIS.
